[57] ABSTRACT

A current transformer assembly includes a shunt circuit connected to a main circuit, the shunt circuit having n number of shunt conductors; a main current transformer for transforming current passing through one of the shunt conductors; and $(n-1)$ number of current balancers having secondary windings connected to each other to enable a circulating secondary current flow. Each of the current balancers is formed of two sub-current transformers so as to fix the ratio of the magnitude of the currents conducted through the individual shunt conductors.

CURRENT TRANSFORMER ASSEMBLY

BACKGROUND OF THE INVENTION

1. Field of the Invention

This invention generally relates to a current transformer assembly and more particularly to a current transformer assembly adapted for use with a circuit of large current high tension power.

2. Description of the Prior Art

In general, a current transformer has primary and secondary windings and an iron core, and is designed so as to transform the primary current through the core and derive out of the secondary winding a current stepped down in proportion to that conducted through the primary winding. Accordingly, it is necessary that the secondary winding current always be exactly proportionate to the primary winding current. However, the conventional current transformer device is of the type where all of the rated current passes through the primary winding and consequently has the drawback that the form of the current transformer device is subject to limitations depending on the magnitude of a rated primary current. For example, where the rated primary current has a relatively small magnitude, for example, 2,000 amperes max., the prior art current transformer device has an upright form, while, when the rated primary current is relatively large, such as 3,000 amperes min., the current transformer device assumes a fallen form. The term "upright form," as used herein, is defined to mean the type of current transformer device wherein the current transformer itself is provided with an iron core and the secondary winding thereof is disposed at the lower part of the current transformer device and the primary conductor is made to extend from the upper part of the current transformer device down to the site of the current transformer itself and then rise through the current transformer back to its starting position at the top of the device. The term "fallen form," as used herein, is defined to mean the type of current transformer device wherein the transformer itself is placed at the upper part or head of the current transformer device and the primary conductor linearly penetrates the core of the current transformer.

The conventional upright type current transformer device requires, as described above, the primary conductor to be first bent downward and then extended upward back to its starting point and consequently has the drawback that it not only presents difficulties in assembly, but also consumes an increased amount of copper from the primary conductor, though it offers an advantage from the standpoint of earthquake resistance. On the other hand, the fallen type current transformer device allows the primary conductor to be used in linear form without being bent and has the advantage of reducing copper requirements for the primary conductor, but is undesirable from the quakeproof point of view. A need therefore, existed for a current transformer assembly which could be built in upright form and effectively operate even in cases where there is to be applied a large rated primary current.

Furthermore, such a current transformer having a fixed rated capacity, with circuits having various current ratings, would offer a great advantage in instituting standardization in the manufacture of current transformer assemblies.

SUMMARY OF THE INVENTION

Accordingly, it is an object of this invention to provide a new and improved quakeproof current transformer assembly adapted to transform large currents.

Another object of the present invention is to provide a new and improved unique current transformer assembly having a construction so as to permit the institution of standardization in the manufacturing of current transformer assemblies.

Briefly, in accordance with this invention the foregoing and other objects are attained by the provision of a current transformer assembly which includes a main circuit having a shunt circuit consisting of n ($n \geq 2$) number of shunt conductors; a

main current transformer for transforming current passing through one of the shunt conductors; and ($n - 1$) number of current balancers connected to the main circuit. The secondary windings of paired subcurrent transformers which constitute respective current balancers are connected to each other to provide a circulating secondary current flow so that the balancers will jointly act to fix the ratio of the magnitude of the currents introduced through the shunt conductors.

Since the magnitude of the current flowing through the conductors constituting the shunt circuit are maintained in a prescribed ratio by the action of the current transformers, only one of the shunt conductors is required to be connected to the main current transformer. This resolves the problem encountered with the prior art current transformer device wherein if a large current were to be introduced through the main conductor of the main circuit, difficulties would occur in constructing the device in an upright form. Moreover, the fact that a main current transformer having a certain fixed rated capacity can be used with respect to various ratings of current passing through the main conductor simply by changing a shunt circuit, permits the standardized manufacture of a current transformer device.

The subcurrent transformers may be connected only to the shunt circuit or both the main conductor and the shunt circuit. Furthermore, where the secondary windings of the subcurrent transformers are provided with a plurality of switch taps and connected to each other so as to enable a circulating secondary current flow, then selective operation of any of the taps will permit control of the ratio between the magnitude of the currents passing through the shunt conductors.

BRIEF DESCRIPTION OF THE DRAWINGS

A more complete appreciation of the invention will be readily obtained as the same becomes better understood by reference to the following detailed description when considered in connection with the accompanying drawings wherein:

FIG. 1 is a longitudinal sectional view of an upright type current transformer assembly according to an embodiment of this invention;

FIG. 2A is an electric circuit diagram of FIG. 1;

FIG. 2B is a sectional view of a current balancer included in the embodiment of FIG. 1;

FIG. 3 is an electric circuit diagram showing the relationship of the main current transformer and the subcurrent transformers where three conductors are used in the shunt circuit of FIG. 1;

FIG. 4 is a longitudinal sectional view of an upright type current transformer assembly according to another embodiment of the present invention;

FIG. 5 is an electric circuit of FIG. 4;

FIG. 6 is an electric circuit showing the interconnection of the main current transformer and the subcurrent transformers where for the case of three shunt conductors are used in FIG. 4; and

FIGs. 7 and 8 respectively are circuit diagrams showing the interconnection of the shunt conductors and subcurrent transformers of the embodiments of the invention when provided with switch taps.

DETAILED DESCRIPTION OF THE PREFERRED EMBODIMENTS

Referring now to the drawings wherein like reference numerals designate identical, or corresponding parts throughout the several views, and more particularly to FIG. 1 thereof wherein the main circuit is shown as including a main conductor 1 connected to a source (not shown), a shunt circuit 2, having shunt conductors 2a and 2b and another main conductor 3, connected to a load. A current balancer 4a is provided across the shunts to fix the ratio of the magnitude of the currents passing through the shunt conductors 2a and 2b. An intermediate part 15 of the shunt conductor 2b extends

downward and penetrates an annular core 5a about which is wound the secondary winding 6 of a main current transformer 5 to thereby constitute its primary winding. The shunt circuit 2 is integrally formed with the current balancer 4a and received in a casing 7. The main conductors 1 and 3 are drawn out through insulation bushings 8. The main current transformer 5 is enclosed in a casing 9 and leads 10 of the secondary winding are drawn outside of the casing 9. A ring-shaped bushing support 13 is fixed to the upper cap of the casing 9. An insulation bushing 14 is fitted in a conventional manner to the inner wall of the ring support 13. The balancer casing 7 is fixed to the upper end of the insulation bushing 14. The aforementioned intermediate conductor 15 of the shunt conductor 2b penetrates an insulation material 16 disposed in the bushing 14. The outer wall of the insulation material 16 is surrounded by a condenser formed of several layers of aluminum foil 12 thereby enabling a uniform potential gradient from the intermediate conductor 15 to the outside to be realized. Both casings 7 and 9 are filled with an insulation oil or gas. These insulation fluids communicate with each other through a passage 17 formed in the bushing 14.

As shown in FIG. 2B, the current balancer 4a includes a subcurrent transformer 18a which is penetrated by the shunt conductor 2a acting as a primary conductor and a subcurrent transformer 18b which is penetrated by the shunt conductor 2b acting similarly as a primary conductor. The secondary windings 19a and 19b of the subcurrent transformers 18a and 18b are connected to cause a circulating secondary current to flow to each other, that is, the different polarities thereof are connected. It should be understood that the circuit of the current transformer assembly of FIG. 1 may be schematically indicated by an equivalent circuit given in FIG. 2A. In this figure, I_0 denotes the total current passing through the main conductor 1, I_1 the current of the shunt conductor 2a, I_2 the current of the shunt conductor 2b, I_c a circulating current through the secondary windings 19a and 19b, and 20 a load to the main current transformer 5.

The aforementioned current transformer assembly of this invention enables the shunt currents I_1 and I_2 to be maintained in a prescribed ratio by the action of the current balancer 4a and the main current transformer 5 will carry out transformation in a fixed ratio, so that the total current I_0 of the main conductor 1 can be accurately measured.

With the ratio of the shunt current I_1 to the shunt current I_2 being represented by K_1 and the ratio of transformation conducted by the main current transformer 5 being represented by K_2 , then the ratio K of transformation effected by the current transformer assembly of the present invention may be expressed by the following equation:

$$K = (K_1 + 1)K_2 \dots 1.$$

Now let the number of turns of the primary and secondary coils of the subcurrent transformer 18a be designated as T_{A1} and T_{A2} , the number of turns of the primary and secondary coils of the subcurrent transformer 18b as T_{B1} and T_{B2} , the ratio of transformation carried out by the subcurrent transformer 18a as $K_A = T_{A2}/T_{A1}$ and the ratio of transformation by the subcurrent transformer 18b as $K_B = T_{B2}/T_{B1}$. Now when a circulating current I_c is conducted through the current balancer 4a, the excitation ampere-turns AT_A and AT_B remaining in the cores of the respective subcurrent transformers 18a and 18b may be expressed as

$$\left. \begin{aligned} AT_A &= I_1 \cdot T_{A1} - I_c \cdot T_{A2} \\ AT_B &= I_2 \cdot T_{B2} - I_c \cdot T_{B1} \end{aligned} \right\} \dots 2.$$

In general, with a current transformer AT_A and AT_B are negligibly small and as such the following equation results:

$$\left. \begin{aligned} I_1 \cdot T_{A1} &= I_c \cdot T_{A2} \\ I_2 \cdot T_{B1} &= I_c \cdot T_{B2} \end{aligned} \right\} \dots 3.$$

When the ratio of I_1 to I_2 in establishing the above equation (3) is denoted by K_1 , and I_1 and I_2 are supposed to have a relationship of $I_1 > I_2 K_1$, it will be apparent that AT_A will become positive and AT_B negative. The positive ampere-turns AT_A will generate a voltage acting to decrease the shunt current I_1 in the primary coil (having turns T_{A1}) of the subcurrent trans-

former 18a and the negative ampere-turns AT_B will produce a voltage acting to increase the shunt current I_2 in the primary coil (having turns T_{B1}) of the subcurrent transformer 18b.

Since regulation of the shunt current is automatically carried out, the ratio of the shunt currents, i.e., $I_1/I_2 = K_1$ attained at the final equalization may be given as

$$K = \frac{KA}{KB} = \frac{T_{A2}}{T_{A1}} \cdot \frac{T_{B1}}{T_{B2}} \dots (4)$$

15 By substituting the value of K_1 in equation (4) above, the ratio K of transformation performed by the current transformer assembly as a whole may be determined.

The arrangement of the current transformer assembly of this invention as described above will make the following facts

20 easily understood. Since only a part of the current of the main conductor 1 is required to be supplied to the main current transformer 5, it is easy to construct the current transformer assembly of the present invention in an upright form and also to reduce temperature rises in the main current transformer 5.

25 Further, a main current transformer of the same construction can be used with various magnitudes of current simply by changing the shunt circuit and current balancer according to the current of the main conductor thus making it possible to standardize the form of the main current transformer.

30 When a far longer rated current is to be introduced through the main conductor 1, the current transformer assembly of the present invention can effect transformation in a still larger current transformation ratio simply by using an increased number of shunt conductors. FIG. 3 illustrates an electric circuit corresponding to FIG. 2A, but including shunt conductors 2a, 2b and 2c. In the case of FIG. 3, a current balancer 4b is provided between the shunt conductors 2a and 2b and another current balancer 4c is provided between the shunt conductors

35 2b and 2c. The shunt conductor 2c is connected to the main transformer 5. The current balancers are of an arrangement similar to that of FIG. 2A and are thus designed to stabilize the current passing through the two shunt conductors associated therewith. Now let the ratio of current transformation con-

40 ducted by subcurrent transformers 18c, 18d, 18e and 18f be represented by K_A , K_B , K_B' and K_C and chosen so as to have a relationship of $K_A = K_B = K_B' = K_C$. Then it will be apparent that the ratio of the currents I_1 , I_2 and I_3 passing through the shunt conductors 2a, 2b and 2c. In the case where many shunt

45 conductors are used, as described above, it will be apparent that in actual operation it is possible to change the number n of shunt conductors to be used by arranging an arbitrary number thereof so as to be detachably fitted to, for example a known blade.

50 It should be understood that the current balancers need not always be connected only to a shunt conductor, but may be coupled, as shown in FIG. 4, with the shunt conductor and main conductor with a prescribed relationship maintained therebetween. According to the embodiment of FIG. 4, a subcurrent transformer 18g is connected to the shunt conductor 2b and another subcurrent transformer 18h is connected to the main conductor 1. The respective secondary windings 19g and 19h of the subcurrent transformers 18g and 18h are connected to cause a circulating secondary current to flow to each other as illustrated in FIG. 5. That is, the paired subcurrent transformers 18g and 18h jointly constitute a current balancer.

55 Now let the current of the main conductor 1 be represented by I_0 , and the currents of the shunt conductors 2a and 2b respectively I_1 and I_2 , as shown in FIG. 5, the ratio of I_0/I_1 by K_3 and the ratio of transformation by the main current transformer 5 by K_2 . Then the ratio of transformation by the current transformer assembly as a whole may be given as

$$K = K_3 \cdot K_2 \dots 5.$$

Now let the number of turns of the primary coil of the subcurrent transformer $18h$ be denoted by T_{A1} , the number of turns of the secondary coil thereof by T_{A2} , the ratio of transformation by the subcurrent transformer $18h$ by $K = (T_{A2}/T_{A1})$, the number of turns of the primary coil of the other subcurrent transformer $18g$ by T_{B1} , the number of turns of the secondary coil thereof by T_{B2} and the ratio of transformation by the other current transformer $18g$ by $K_g = (T_{B2}/T_{B1})$. Now when a circulating secondary current I_c is introduced excitation ampere-turns AT_A and AT_B will be left in the cores of the subcurrent transformers $18h$ and $18g$ and be expressed by the equation (6) below.

$$\begin{aligned} AT_A &= I_0 T_{A2} - I_c T_{A2} \\ AT_B &= I_0 T_{B1} - I_c T_{B2} \end{aligned} \quad \{ \dots \quad 6.$$

In general with a current transformer the ampere-turns are negligibly small, so that the following equation results:

$$\begin{aligned} I_0 T_{A1} &= I_c T_{A2} \\ I_0 T_{B1} &= I_c T_{B2} \end{aligned} \quad \{ \dots \quad 7.$$

Where, therefore, I_0 and I_c have a relationship $I_0 > I_c K_3$ (where K_3 represents the ratio of I_0 to I_c when the equation (7) above is established), then the ampere-turns AT_A will become positive and the ampere-turns AT_B negative. The positive ampere-turns AT_A will generate a voltage acting to decrease the current I_0 of the main conductor 1 in the primary coil (having turns T_{A1}) of the subcurrent transformer $18h$ and the negative ampere-turns AT_B will generate a voltage acting to increase the shunt current I_c in the primary coil (having turns T_{B1}) of the subcurrent transformer $18g$. Thus the ratio of I_0/I_c is controlled to have a fixed value. The ratio $K_3 = (I_0/I_c)$ of transformation is expressed as

$$K_3 = \frac{KA}{KB} = \frac{T_{A2}}{T_{A1}} \cdot \frac{T_{B1}}{T_{B2}} \quad (8)$$

Therefore, the ratio K of transformation by the current transformer assembly of FIG. 4 may be determined by substituting the value of the equation (8) in equation (5). It should be understood that the current transformer assembly of FIG. 4 will attain the same objects as that of the embodiment of FIG. 1.

Furthermore, it should be apparent that the present invention will enable a much larger rated current to be measured by a main current transformer having a fixed rated capacity simply by adding more shunt conductors. When shunt conductors $2a$, $2b$ and $2c$, as shown in FIG. 6, are used it is necessary to connect only subcurrent transformers $18i$ and $18g$ to the main conductor 1, a subcurrent transformer $18i$ to the shunt conductor $2b$ and a subcurrent transformer $18g$ to the shunt conductor $2c$ and to connect the two secondary windings of the subcurrent transformers $18i$ and $18g$ and to connect the two secondary windings of the subcurrent transformers $18g$ and $18i$ to cause a circulating current to flow. It will be apparent that proper selection of the ratio of transformation by the respective subcurrent transformers can fix the ratio of the currents I_1 , I_2 and I_3 of the shunting conductors.

In application of this invention, the ratio of the magnitude of the currents passing through the shunt conductors is computed by basing the same on the ratio of transformation performed by the subcurrent transformers. In actual use it has

been found that sometimes a slight error occurs in the ratio of the shunted current. In order to avoid such errors, it is preferred that the secondary windings of the subcurrent transformers each be provided with a plurality of switch taps t_1 to t_n , as shown in FIGS. 7 and 8. By the action of such switch taps, the ratio of the magnitude of the currents passing through the shunt conductors can be minutely and precisely controlled and adjustments can be easily effected even after the current transformer assembly is fully set up.

10 Obviously, numerous modifications and variations of the present invention are possible in the light of the above teachings. For example, it is possible with the present invention to provide a shunt circuit including current balancers which are separate from the main current transformers.

15 It is therefore to be understood that within the scope of the appended claims the invention may be practiced otherwise than as specifically described herein.

What is claimed as new and intended to be secured by letters patent of the United States is:

1. A current transformer assembly comprising:
a main circuit including a shunt circuit having n number ($n \geq 2$) of shunt conductors;
a main current transformer for transforming current passing through one of the shunt conductors included in said shunt circuit; and
($n-1$) number of current balancers connected to the main circuit each of which is formed of a pair of subcurrent transformers and wherein the secondary windings of each pair of subcurrent transformers are connected to each other with different polarities through terminals on each of said secondary windings so as to cause a circulating current flow such that the balancers will jointly act to fix the magnitude of the currents passing through the shunt conductors.

35 2. A current transformer assembly according to claim 1, wherein the subcurrent transformers constituting said ($n-1$) number of current balancers are connected to the shunt circuit.

3. A current transformer assembly according to claim 1, 40 wherein the ($n-1$) number of current balancers comprises:

($n-1$) number of first subcurrent transformers connected to a main conductor through which is introduced the total current of the shunt circuit;

($n-1$) number of second subcurrent transformers connected to the shunt circuit; and

wherein each of said balancers consists of one first subcurrent transformer and one second subcurrent transformer.

4. A current transformer assembly according to claim 1, 50 wherein the secondary windings of the current transformers constituting the current balancers are provided with a plurality of switch taps so as to vary the ratio of the magnitude of the currents passing through the shunt conductors.

5. A current transformer assembly according to claim 1, 55 wherein the main current transformer and current balancers are respectively received in a main current transformer casing and a balancer casing each of which are filled with an insulation fluid, and wherein the balancer casing is supported above the main current transformer casing through a bushing provided with a passage for the insulation fluid and is penetrated by the primary conductor of the main current transformer.

* * * * *
